TURNSTILE

Soren Madsen, Bergenfield, N. J., assignor of one-fourth to Joseph F. O'Brien, Englewood, N. J.

Application October 19, 1935, Serial No. 45,735

7 Claims. (Cl. 194—61)

This invention relates to improvements in coin-actuated turnstiles, and particularly to mechanically-actuated turnstiles in which a coin itself is utilized as a mechanical member of the operating mechanism instead of acting to close an electric circuit.

One of the objects of this invention is to provide, in a turnstile, mechanical means whereby a manually-rotated member of a turnstile may be utilized as a carrier to carry or swing a coin in a horizontal arcuate path and the coin in this swinging movement may be utilized to operate release mechanism so as to enable a continuing operative movement of the turnstile.

15 Another object of my invention is to provide mechanism of the type specified which will enable a coin of unit-fare value to produce a single operative movement of the turnstile and to enable a coin of multiple fare value to produce multiple operative movements of the turnstile.

Another object of my invention is to produce in a turnstile of the character described mechanism whereby a coin of unit fare value will be carried in an arcuate path throughout a single operative movement of the turnstile and a coin of multiple fare value will be carried throughout a multiple number of operative movements in accordance with the value of the coin.

Still another object of my invention is to provide mechanism including a turnstile-release element and mechanism for feeding one coin at a time to the coin-carrier whereby the coin during its manual movement in an arcuate path will be utilized first to operate releasing mechanism to effect an operative movement and second, to reset the coin-feeding mechanism and to provide for the accomplishment of these results by coins of single unit fare value or coins of multiple unit-fare value.

40 Another object of this invention is, in a turnstile of the type specified, to provide mechanism which will enable one operative movement of the turnstile to be effected by a coin of relatively large diameter such as a nickel, and will enable multiple operative movements by a coin of smaller diameter such as a dime.

Still another object of my invention is in a turnstile mechanism of the type specified, to provide for guiding a coin having a multiple fare value through multiple operative movements and in each movement to operate the mechanism of the turnstile and at the end of the multiple operative movements to reset the coin feed mechanism for a succeeding coin.

55 Still another object of my invention is to provide a rotating coin-carrying element of a turnstile adapted to carry coins of single and multiple fare values combined with a single coin-counter operable to register each of said coins in accordance with the proper fare value thereof.

Another object of my invention is the provision in a device of the character described of a coin-feeding element adapted to hold a plurality of coins but controlled by the movement of each coin fed to the carrier mechanism whereby a single coin will be fed at a time to said carrier mechanism and a succeeding coin will be released and fed at a time to said carrier mechanism and a succeeding coin will be released and fed to said carrier mechanism only after said turnstile has completed the number of operations or movement equivalent to the fare value of the preceding coin deposited. In general terms, my invention comprises the provision in a device of the character described having a rotatable coin-carrying element and a release mechanism for the turnstile of selective means for causing coins of varying diameters to be positioned in varying vertical positions in said rotatable coin-carrying element and the provision of a plurality of arcuate coin-guiding elements cooperating with said coin-carrying element to cause a single releasing operation to be effected by a coin of unit fare value to provide for a unit movement upon such release by said coin of unit value and also to cause a coin of greater fare value to move through a greater arc and to operate the turnstile-releasing means a plural number of times, thus providing for a number of operative movements of the turnstile in accordance with the value of the coin.

More particularly my invention comprises the employment, in combination with the coin-carrying and coin-guiding elements hereinabove specified, of feed-controlling means resettable by the movement of the preceding coin and operable to permit a coin to be fed to the coin-carrying and guiding mechanisms only after the preceding coin has moved through one or more arcs in accordance with the fare value of such preceding coin and includes means adapted, in case of plural fare value coins to carry such plural fare value coins over the chute or drop for a coin of lesser value.

My invention also preferably provides means for locking the turnstile against reverse movement after release thereof and means whereby said locking means against reverse movement may be released to permit such reverse movement and operation when desired.

With these and other objects in view, the invention comprises the combination of members and arrangement of parts so combined as to coact and cooperate with each other in the performance of the functions and the accomplishment of the results herein contemplated, and comprises in one of its adaptations, the species or preferred form illustrated in the accompanying drawings, in which:

Fig. 1 is a view in side elevation of a turnstile embodying my invention;

Fig. 2 is a plan view of the turnstile shown in Fig. 1;

Fig. 3 is a fragmentary vertical section on the line 3—3 of Fig. 1 illustrating the upper portion 5 of the turnstile shown in Fig. 1 and showing the coin-actuating mechanism and the coin-feeding mechanism in coin-receiving position;

Fig. 3a is a fragmentary section similar to Fig. 3 showing the coin-feeding mechanism in a slot-obstructing position;

Fig. 4 is a top plan view of the mechanism of the turnstile with the cover removed therefrom;

Fig. 5 is a section on the line 5—5 of Fig. 3, looking in the direction of the arrows;

Fig. 6 is a section on the line 6—6 of Fig. 3, looking in the direction of the arrows;

Fig. 7 is a section on the line 7—7 of Fig. 3, looking in the direction of the arrows;

Fig. 8 is a section on the line 8—8 of Fig. 3, looking in the direction of the arrows;

Fig. 9 is a section on the line 9—9 of Fig. 4 looking in the direction of the arrows;

Fig. 10 is a section on the line 10—10 of Fig. 6 looking in the direction of the arrows;

Fig. 11 is a section on the line 11—11 of Fig. 3 looking in the direction of the arrows;

Fig. 12 is a section on the line 12—12 of Fig. 3 looking in the direction of the arrows;

Referring now to these drawings, which illustrate a preferred form of my invention, I designates a turnstile base, 2 indicates a suitable vertically-disposed turnstile casing mounted on said base 1 and 2' indicates a removable cover. The said casing and cover enclose an axially-disposed stationary shaft 3, suitably mounted on the base 1, and 4 indicates a sleeve rotatably mounted on said shaft and having fast on its upper end a coin-carrier head 5 disposed above a rotatable shelf 6 also fast on said sleeve on the lower surface of which shelf is pivotally mounted a plurality of foldable arms 7. As shown, four of the arms 7 are employed, each pivotally mounted in a depending bracket 7a and adapted to be moved pivotally from vertical to horizontal 45 positions about pivot 7'. The casing 2 is provided at one side thereof with a projecting cam plate 8 adapted during the rotary movement of the shelf 6 to successively engage each of the arms 7 adjacent to the pivoted portion and to cause each of the said arms to be raised and projected from vertical into horizontal position in order to close a passageway.

Fast on the sleeve 4 above the shelf 6 is a coin-carrying head 5 which is provided with a series 55 of radial slots 10 corresponding in number to the number of arms of the turnstile. Each of these radial slots is arranged to provide a plurality of communicating coin holders and, as shown, two coin-holder portions are formed of different 60 depths and adapted respectively to receive a nickel and a dime. The coin holder portions are formed one below the other, and in the form of my invention shown, the depth of the radial slot is increased to provide holder steps 10', 10" as more particularly shown in Fig. 10. These 65 radial coin slots 10 are adapted to register with a coin slot of a coin-feeding mechanism herein-after described which is adapted to feed one coin at a time to that one of the radial coin-slots in 70 the head 5 which is in registration therewith. Suitable registering mechanism is provided to cause the turning of the head 5 so as to provide accurate registration between the radial coin slots and holders and the coin slot of the feed mechanism. As illustrated, I provide mechanism 75

for yieldingly resisting the manual turning of the sleeve 4 and turnstile parts about the shaft 3 and bringing the same to a stop after each quarter of a revolution which comprises a four way cam 11 fast on the sleeve 4 cooperating with 5 a pair of spring-pressed links 12 pivotally mounted on the casing 2. The cam 11 is provided with four rounded depressions and four rounded projections, so that upon a manual turning of the sleeve 4 about the shaft 3 the said sleeve 10 and the head which is fast therewith may on one push (the extent of which is limited and restricted by the locking mechanism hereinafter described) be turned through a quadrant or quarter of a revolution and will then stop. The bottoms of the depressions 11' of the cam 11 will be arranged to stop in registration with the radial coin-slots in the head 5 and with the arm 7.

In accordance with my invention, a coin is fed from the coin-feed mechanism into one of these radial slots and mechanism is provided in cooperation with these slots for guiding the coin so fed in an arc of a circle during the manual movement of the turnstile through manual pressure on one of the arms 7, this pressure being applied during the passage of a person through an entrance which is obstructed by one of these arms when in extended position.

When the turnstile is turned through a quarter of a revolution as hereinabove described it will be locked by a suitable locking mechanism in that position, and in the preferred form of my invention illustrated, I provide on a stationary shelf 13 (supported on the casing 2 below the rotating shelf 6) a locking block 14 which is 35 adapted to engage the heel 15' of one of four locking pawls 15 which are pivoted at 15a in slots in the rotating shelf 6 to extend above and below said shelf 6. Said pawls 15 have their upper ends 15b extending above the shelf 6 and adapted 40 to be engaged by releasing mechanism operable by engagement with the coin during its arcuate movement in a radial slot 10 of the coin carrying head 5 as hereinabove specified.

A coin fed into the radial coin-slot 10 of the 45 coin-carrying-head is guided in its arcuate movement by one of a pair of arcuate rails which co-operate with said radial slots 10 and engage an edge of one of the coins in accordance with the extent or size of the diameter of the coin which 50 is fed thereto. Thus, if a nickel is fed to one of the radial coin-slots in the head, it will be engaged at two points on its periphery between the inner edge or wall of the slot and the upper rail 18, and if the coin is a dime and of smaller diameter it will pass through the space between the said inner wall of the coin slot and the upper rail and will seat itself and be supported at two 55 points in its periphery between the upper edge of the lower guide rail and the lower edge of the upper guide rail, these rails and the slot at this position being adapted to engage and guide coins of smaller diameter as more particularly illustrated in Figs. 3, 9, and 10.

By providing guide rails of varying lengths for 65 coins of varying diameters which are also of varying values, I am enabled to utilize a coin of predetermined diameter a plurality of times for producing a plurality of operative or effective movements of the turnstile.

Each effective movement of the turnstile will comprise, as above indicated, a turn of a quarter of a revolution, and in each of these turns, I utilize the coin to release the locking engagement 70 between one of the pawls 15 and the locking block 75

14 and in said movement I also provide for a counting movement of a counter in order to register a fare or the passage of a person through the turnstile. In the embodiment shown, the release mechanism comprises a vertical crank rod 16 pivoted at 16^a in an upper stationary shelf 17 fastened directly on the shaft 3 through the hub 17. This vertical crank rod 16 is provided with a pair of coin-contacting arms 16', 16'' movable respectively by a nickel and a dime and one of which extends into the path of a nickel when moved or carried through the arc of a quarter of a revolution hereinabove described, and the other extends into the path of a dime.

15 When the roller and cam mechanism 11 brings the turnstile to a stop, the parts will be so positioned that there will be a slight space between the heel 15' of the pawl 15 and the locking block 16, so that there will be an initial free but restricted movement of the turnstile, and this free movement is utilized to permit a coin seated in the radial coin-slot to engage one of the arms 16', 16'' and to turn the crank rod 16. It will be understood that the heel 15' if no coin has been inserted, will engage block 14 before arm 16^b engages the upper end of pawl 15^b. In case a coin engages arm 16' or 16'', the arm 16^b is turned counter-clockwise as viewed in Fig. 6 so as to engage the top 15^b of pawl 15 before heel 15' reaches block 14 which will cause an arm 16^b at the lower end of said crank rod 16 to engage an inclined surface on the upper end of the pawl 15^b and to swing the same about its pivot 15^a so as to lift the heel 15' out of engagement with the locking block 16, and thus to release the turnstile for a complete operative movement or quarter revolution. This movement will bring one of the other pawls 15, four of which are employed into locking engagement with the block 14, but owing to the action of the cam 11 and links 12 will recede slightly therefrom to allow for the aforesaid initial free movement.

16 The coin-guiding rails hereinabove specified are arcuate in conformation and extend partially around the surface of the coin carrier in such proximity and position in relation thereto as to engage during the arcuate movement thereof one or more points on the peripheral edge of the coin, another part of the coin being engaged by the wall of the slot. Thus the coin rail 18 for the nickel will be spaced a greater distance from the periphery of the coin-carrying head than the rail 19 for the dime. The rail 18 is more particularly shown in Fig. 5 and the rail 19 is so shown in Fig. 6. It will be seen from Fig. 5 that the nickel rail 18 extends only for a quarter of a circle and terminates above a coin chute 20 adapted to receive nickels. A nickel supported on this rail will in its arcuate movement first engage the arm 16'' to operate the release mechanism and will thereafter be guided to the end 18' of the rail 18 off which it will drop into the coin slot 20. During the latter part of this movement, however, the coin will engage and operate a resetting mechanism for the coin-feeding device which will then permit another coin to be fed into the radial slot which is in registration therewith for another operative movement of the turnstile. This coin-feed mechanism will be hereinafter described, but at present I will merely say that the nickel engages the arm 21' of the lever 21 which is pivoted at 21^a and swings the said lever 21 to cause the opposite end 21^b to operate the resetting mechanism of the coin-feed device.

17 Assuming now that the coin-feed device has

fed into a radial slot, a dime, instead of a nickel, the dime being of smaller diameter will pass through the space between the rail 18 and the wall 11 of the slot and will drop down onto the supporting rail 19, so that a point in its lower peripheral edge is engaged thereby. Another point in its peripheral edge at the opposite side of its center will also be engaged by the lower edge of the rail 18 while a segment thereof fits within a rail slot. An initial movement of the turnstile through the arm 7 will thus cause a dime in its operative movement to engage the arm 16' of the crank rod 16 to release the pawl 15 from locking engagement with the block 14, whereupon further effective movement of the turnstile may be accomplished while the dime rests upon the part 19' of the rail 19. When it reaches the end of this part 19', it will be guided by engagement with the spring pressed arm 19^a over the coin chute 20 and across the outward bend 19^b in the rail 19. So soon as it crosses this bend 19^b it will be held between the rail portion 19^d and the inner wall of the coin slot. It will in its second movement then engage the arm 16^e of an auxiliary crank rod 16^c which is so connected by the arcuate rod 16^d to the crank rod 16 as to cause an operative movement of the releasing arm 16'' into releasing engagement with the end 15^b of that one of the four pawls which is in locking relationship with the locking block 14. After such releasing movement, the dime will be carried around in a second arcuate movement in engagement between the part 19^d of the rail 19 and the inner wall of the slot as shown in Fig. 10 and will finally drop off the end thereof into the coin chute 20^a for dimes. During its last-mentioned movement along the part 19^d of the rail 19, the dime will engage the end 22' of the arcuate rod 22 which is also pivoted at 21^a and has its opposite end 22^a adapted to engage and actuate resetting mechanism of the coin-feeding device to enable another coin to be fed to the coin-carrier.

18 I will now describe the coin-feed mechanism which is more particularly shown in Figs. 3, 3a. 45 This mechanism comprises a coin chute 23, the coin-slot 23' of which is provided at its lower end with a feed member 24 adapted to feed only one coin at a time to the lower end of the slot and thus to the coin-carrying head. This feed member comprises a three-way lever pivoted at 24' to the walls of the chute and adapted to provide a seat 24^a for a segment of the coin when it is fed downwardly into the slot. This three-way lever has another member or arm 24^b which is adapted to turn inwardly about the pivot 24' when a coin is dropped through the chute by the seating portion 24^a and is also provided with a downwardly extending portion 24^c which is provided with a locking pin 24^d adapted when the slot is free of coins to rest beneath pawl member 25 so that when a coin is passed through the slot and engages the seating portion 24 the lower end of the lever 24^c will swing outwardly and the pin 24^d will be engaged by the notch 25' of said pawl member 25 as more particularly shown in Fig. 3a. This movement of the device 24 will occur with the weight of any coin and will therefore only let one coin pass at a time because as aforesaid the upper member 24^b will move into slot-obstructing position and prevent passage through the seat of further coins until the pin 24^d is released from locking engagement with the notch 25' of the pawl lever 25. It will be understood that the member 24 is properly bal- 75

anced to cause the tilting into slot obstructing position by the weight of the coin.

In order to feed a second coin, therefore, past the feed member 24 it is necessary that the pin 24^b be released to permit the member 24 to swing into its coin receiving position, and this is accomplished by lifting the pawl member through the medium of the lifting lever 26, which is pivoted at 26^a has its upper end 26^a in engagement with the pawl member 25 and its lower end 26^b normally pressed outwardly by the spring 26^c into non-lifting position. When a nickel engages the end 21^b of the pivoted rod 21, the opposite end 21^b will engage the lower end of the lifting lever 26 to cause a lifting movement thereby of the pawl member 25 to release the same from engagement with pin 24^c and permit the feed element 24 to swing back into normal coin-receiving position. When a dime reaches and contacts with the end 22^b of the arcuate pivoted rod 22 the opposite end 22^a thereof will likewise engage the lifting lever 26 and produce a similar engagement of the pawl to release the feed member and permit the same to move into coin receiving position. Thus only one coin at a time can be fed through the feed member 24 though a slot above this feed member may if desired be long enough to contain additional coins.

It will be seen from the above that I have provided mechanism whereby a coin of unit-fare value such as a nickel will be adapted to produce a single effective movement of the turnstile and a coin of greater or multiple unit fare value will be adapted to produce multiple effective movements in accordance with the multiple value thereof.

In the preferred embodiment of my invention, I provide means adapted to cause registration on a counter during each effective or operative movement of the turnstile and I am thus enabled to register on a single counter coins of unit-fare value and of multiple fare-value as they pass through the coin-actuating mechanism of the turnstile. As illustrated, I provide a single counter 27 mounted on the shelf 17. The counter 27 has a countershaft 27^a provided with a spring pressed pawl 27^a which is adapted to make a registering movement against the action of a spring 27^b and I provide means adapted during each operative movement of the turnstile to produce one movement of the pawl 27^a to provide for a single count on the counter. This movement is accomplished by pivotally mounting a lever 28 on a depending bracket 29, which lever 28 is pivoted at 28^a and is adapted, at its lower end to engage blocks 29^b and is formed in two parts held together for movement in one direction by a spring 28^b, and thus to cause movement of the upper end 28^c of the lever only during movement in one direction of the turnstile, it being understood that if the turnstile is moved in the opposite direction the end 28^c will bend at the pivot 28^d against the action of the spring 28^b and no movement of the upper end of the lever will occur while at the same time such upper end will be held in proper position for its next registering movement.

It is desirable in devices of the character specified that so soon as the effective or operative movements have begun, that any reverse movement shall be prevented and for this purpose I have provided the pawl 15 with a tooth 15^c adapted to engage in an effective movement of the turnstile with a plurality and preferably four teeth or locking notches 30, 30', 30^a, and 30^b

formed on members 31, 31' mounted on the upper surface of the shelf 13 in the path of the lower end of the pawl 15.

Under some conditions it is desirable that the turnstile be permitted to have a reverse movement as for example when it is desired to unload a bus in which the turnstile is used to admit and register passengers. Under such conditions I have provided a series of spring-pressed rods 32, 32', 32^a, and 32^b adapted to be elevated in front of the teeth 30, 30', 30^a, and 30^b so as to close the notches of such teeth and provide a surface permitting pawls to ride over the same without engagement therewith. As illustrated, these spring-pressed rods are mounted upon a horizontal common bar 33, which is capable of being elevated by a vertical bar 34 operated by nob and catch member 35 adapted to be engaged or disengaged from a notch 35' in the wall of the casing. Obviously, upon upward movement of the member 35 and a swinging of the same into the notch 35' the bar 33 will force the rods 32, 32', 32^a, 32^b upwardly against the action of the springs 32^c, 32^d, 32^e, and 32^f, thus nullifying the effect of the teeth 30, 30', 30^a, and 30^b and allowing a reverse movement.

At times a coin, such as a penny which is not of unit-fare value or multiple fare value will be deposited and it is desirable to return such coin. For this purpose the rail 18 for the nickel is so positioned as to prevent the downward passage beyond the same of a penny or a coin having a diameter intermediate the nickel and the dime, so that a penny will be mounted upon this nickel rail, the releasing arm 16^a however will be so positioned in relation to the inner wall of the coin slot that the diameter of a penny will be insufficient to engage the same so that a penny will be unable to produce a releasing movement of the pawl 15 and consequently the end of the pawl will strike the locking-block 14 and movement of the arm will be prevented. In order to free the penny from the nickel rail it is only necessary to provide for a slight free reverse movement and when such movement is made by manual engagement of the arm of the turnstile the penny or similar coin will be dropped into a coin return chute 36. In such reverse movement of a penny, the periphery of the penny, however, is adapted to engage one end 37^b of a rocking rod 37, the opposite end 37' of which is adapted to engage the nickel releasing rod 21^b and cause said rod to provide a resetting movement of the lever 26 pawl 25 and feed member 24, thus releasing said last mentioned feed member from slot-obstructing position, and resetting the feed mechanism to permit feeding of coins to the carrier.

In the embodiment of my invention shown, the nickel slot 20 is provided above the platform 6 with a chute 20' supported from platform 17. Below the platform 6, I provide a stationary chute 20^a which leads into a coin-tube 20^c, the bottom end of which communicates with a coin display compartment 2^a having a window 2^b in the wall of the casing 2. Above and registering with the dime slot 20^a and supported from the platform 17 is a coin chute 20^b and below the coin slot 20^a and registering therewith is a coin chute 20^c communicating with the coin tube 20^d, the lower end of which likewise communicates with the display compartment 2^a. The bottom 2^c of this display compartment 2^a is rockable about a pivot 2^e to drop coins into a compartment 2^f which is provided with an inclined bottom 2^g and a pivoted door 2^h operable to permit coins within the com-

partment 2^a to slide out into the hand of the operator.

The bottom 2^c of the compartment 2^a is rocked to drop a coin upon each operative movement of the turnstile by means of the cam 2^e which is fast on the sleeve 4 and the projections of which are adapted to engage the rod 2^d and to rock bottom 2^c for the purpose of dropping the coin displayed in the compartment 2^a on the succeeding revolution of the turnstile.

Having described my invention, I claim:

1. A coin-actuated turnstile embodying, in combination, a manually-rotatable turnstile having arms movable through a predetermined arcuate movement to obstruct and free a passageway, a coin-carrying member rotatable with said turnstile, means for engaging and retaining a coin in said member throughout such predetermined arcuate movement, coin feed mechanism having a coin slot communicating with said coin carrying member and provided with a resettable coin-slot closer adapted to feed one coin at a time to said coin-carrying member, locking mechanism for locking the turnstile against rotary movement, means located in the path of the carried coin and operable thereby to release said locking mechanism to enable said predetermined manual movement of a turnstile-arm, and means also actuated by said coin near the end of its arcuate movement for resetting said coin-feeding mechanism.

2. A coin-actuated turnstile embodying, in combination, a manually-rotatable turnstile having arms movable to obstruct and free a passageway, a coin-carrying member rotatable with said turnstile through a predetermined arcuate movement, means for engaging and retaining a coin in said member throughout such predetermined arcuate movement, locking mechanism for locking the turnstile against rotary movement, a release member located in the path of the coin and operable thereby to release said locking mechanism during said predetermined arcuate movement, and another release element also located in the path of said coin and operable thereby, again to release the said locking mechanism and thus enable a successive arcuate movement of the coin-carrying member, whereby said arms may be released for movement a plurality of times by a single coin.

3. A coin-actuated turnstile embodying, in combination, a manually-rotatable turnstile having arms movable to obstruct and free a passageway, a coin-carrying member rotatable with said turnstile through a predetermined arcuate movement, means for engaging and retaining a coin in said member throughout such predetermined arcuate movement, locking mechanism for locking the turnstile against rotary movement, and lock release members located in the path of the coin and operable thereby to release said locking mechanism a plurality of times by a single coin.

4. A coin-actuated turnstile embodying, in combination, a manually-rotatable turnstile having arms movable to obstruct and free a passageway, a coin-carrying member rotatable with said turnstile and provided with means for engaging and moving a coin in an arcuate path, locking mechanism for locking the turnstile against rotary movement, means located in the path of the coin and operable thereby to release said locking mechanism to enable an operative man-

ual movement of the turnstile, and means for successively feeding coins one at a time to said coin-carrying member, said means including a coin feed member, a movable coin support in said feed member, a movable member in the arcuate path of the coin, and trip connections between said movable member and the coin support.

5. A coin-actuated turnstile, embodying, in combination, a manually-rotatable turnstile having arms movable through a predetermined arcuate movement to obstruct and free a passageway, a coin-carrying member rotatable with said turnstile and comprising a sleeve-like member having a radial slot, coin feed mechanism having a coin slot communicating with said coin carrying member and provided with a resettable coin-slot closer adapted to feed one coin at a time to said coin carrying member, coin-guiding means comprising an arcuate rail adapted to engage a point in the peripheral edge of the coin to support the same during said predetermined arcuate movement of said coin in the slot in said rotatable coin-carrying member, locking mechanism for locking the turnstile against rotary movement, means located in the path of the coin and operable thereby to release said locking mechanism to enable an operative manual movement of the turnstile, and means also actuatable by said coin near the end of its arcuate movement for resetting said coin-feeding mechanism.

6. A coin-actuated turnstile embodying, in combination, a manually-rotatable turnstile having arms movable through a predetermined arcuate movement to obstruct and free a passageway, a coin-carrying member rotatable with said turnstile and comprising a sleeve-like member having a radial slot, means for feeding a coin to said slot, a releasable locking mechanism for locking the turnstile against rotary movement, spaced lock releasing members, and a plurality of arcuate rails arranged to support a coin of one diameter in position to actuate one of said releasing members so as to release said locking mechanism once and to support a coin of a different diameter in position to actuate said releasing members in succession so as to release said locking mechanism a plurality of times, whereby one or a plurality of actuations of the turnstile can be effected.

7. A coin-actuated turnstile embodying, in combination, a manually-rotatable turnstile having arms movable to obstruct and free a passageway, a coin-carrying member rotatable with said turnstile and comprising a sleeve-like member having a radial slot, means for feeding a coin to said slot, locking mechanism for locking the turnstile against rotary movement, spaced lock releasing members, and a plurality of arcuate rails one of which is constructed and arranged to support a coin of one diameter in position to actuate one of said releasing members so as to release said locking mechanism once, and whereof another of said rails is constructed and arranged to support a coin of smaller diameter through a longer arc of movement than a coin of a larger diameter so as to actuate said releasing members in succession whereby one or a plurality of actuations of the turnstile can be effected.

SOREN MADSEN.
